UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed September 12, 1929. Serial No. 392,140.

This invention relates to power interlocking systems, and more particularly pertains to indication means and devices for such systems.

In power interlocking systems, it is desirable for reasons familiar to those skilled in the art, to provide means in the tower for indicating that the switch or signal controlled by a particular lever has properly operated or responded, which indicating means is employed to release or actuate the usual indication latch mechanism governing that lever.

In one type of indication system, sometimes called a battery or constant current indication system, a three-position relay in the tower is controlled over a polarized line circuit from a battery or other suitable source located at the switch machine. This polarized line circuit is governed by contacts operated by the switch machine and track switch jointly, in a manner, that the indicating relay indicates the position and locked condition of the track switch, which relay is employed to actuate the associated indication latch mechanism.

It may happen that an improper or false indication will be given under a certain combination of circumstances in an indication system of the constant current or battery type as above described. For example, when the operator moves a control lever to a new governing position, there is a short interval of time after power is applied to the switch machine during which the contacts associated with the switch machine for controlling the indication relay, remain closed and the indication relay is energized; and, if the operator should quickly return the control lever to its former governing position the indication latch mechanism may be released, even though the operation of the switch machine from its former position has been initiated. Under such conditions, if provisions are made so that the switch machine will automatically reverse and follow the movement of the control lever to its original position, no particularly unsafe condition results; but, if the switch machine should fail to reverse due to the failure of parts, blowing of a fuse by excessive current occurring

by such quick reversal of the control lever, or the like, the inertia of the motor armature and the gearing of the switch machine might unlock the track switch points and even partially move them. This contingency would be unsafe because the control lever would be in one extreme position, although the track switch would be unlocked and partly moved.

With these considerations in mind, it is proposed in accordance with the present invention to provide an electric lock actuated to an active position when power is applied to the switch machine, with its locking member preventing a quick reversal of the control lever while in such a position. Also, this electric lock is to have an electrical construction which causes the locking member to be slow in releasing, sufficiently to assure that the switch machine has come to rest after its circuit for the new governing position has been broken, after which time period the locking member assumes an inactive position and permits the control lever to be returned to its former governing position, in which position the indication latch mechanism may be released, if the switch machine is still in a corresponding extreme position and locked.

Various other objects, purposes and characteristic features of the present invention will be in part obvious and in part pointed out as the description of the invention progresses.

The single figure of the accompanying drawing represents in a diagrammatic manner one specific embodiment of the present invention, as applied to a power operated switch machine, its associated track switch, its control lever and other devices pertaining thereto.

With reference to the single figure of the drawing, a track switch TS is shown as operated by a suitable switch machine SM which is preferably of the type described in my Patent No. 1,466,903 dated September 4, 1923. This switch machine SM has the usual operating mechanism for controlling the track switch TS and is operably controlled over a normal and a reverse control wire 5 and 6 respectively in conjunction with a com-

mon return wire C, in any suitable manner well known to those skilled in the art, one such control being disclosed in my above mentioned Patent No. 1,466,903.

5 The switch machine SM also has associated therewith a group of contacts included within a dotted rectangle designated PD which are known as point detector contacts and are jointly controlled by the track switch TS and the switch machine SM. More specifically, 10 the point detector contacts PD include an insulated block 7 which is controlled to either of two extreme positions in correspondence with the track switch TS when said track switch is locked by its controlling switch machine SM. This insulating contact block 7 assumes an intermediate non-contacting position at any such time that the switch machine SM is in operation and the track switch TS is unlocked. 15 Mounted upon the movable insulated contact block 7 are contacts 8 and 9 which make contact between their respective pairs of fixed contacts when in the normal or reverse extreme positions only.

20 25 A shunt contact 10, biased toward a contacting position, is actuated to a non-contacting position when the movable contact block 7 is in a normal extreme position; also, a similar shunt contact 11, biased toward a contacting position, is actuated to a non-contacting position when the movable contact block 7 is in a reverse extreme position. An example 30 of an operating mechanism for such point detector contacts is disclosed in the patent to C. S. Bushnell, Patent No. 1,517,236 dated November 25, 1924, with the specific construction of such point detector contacts including shunt contacts being formed in any suitable manner, such for example as shown in an 35 application by J. C. Lindner Ser. No. 385,172 filed August 12, 1929.

40 Associated with the point detector contacts PD, there is a local transformer T, the primary of which is supplied with alternating current potential from a suitable alternating current source over a transmission line extending from an interlocking tower.

45 In the tower, a control lever L is provided, which is capable of assuming the usual full normal and full reverse positions indicated by the arrows N and R respectively as they appear opposite the arrow A on the control lever L. These full positions of the lever L are supplemented by normal and reverse indicating positions designated by the arrows NI and RI respectively, which indicating positions are determined by an indication latch mechanism IM conventionally shown as including an indication magnet 15 and a locking plunger 16. The movement of the lever L, from a full position to an indication position, operates a tappet bar 17 from a corresponding extreme position to a central position by means of a cam slot 18, for controlling the associated mechanical interlocking

between levers in the usual well known manner.

70 The lever L governs the operation of the switch machine SM over normal and reverse operating wires 5 and 6 in conjunction with a common wire C by means of movable contact members 12 and 13. These movable contact members 12 and 13 together with movable contact member 14 make contact between certain pairs of fixed contacts when the lever L is in the positions N and NI, and make contact between certain other pairs of fixed contacts when the lever L is in the positions R and RI. A fuse F is associated with the switch machine operating contacts to prevent excessive overloads.

75 Preferably, a suitable electric lever lock is employed with the lever L to prevent movement of said lever from its normal position N and its reverse position R when the detector track section associated with the switch TS is occupied, however, such a lock has been omitted to simplify the description of the present invention.

80 Associated with the indication latch mechanism IM is a SS relay having a local phase winding 20 and a line-phase winding 21, which windings operably control a contact 22 to either of two extreme positions depending upon the relative instantaneous polarity of the alternating current flowing in the two windings. This contact 22 assumes a deenergized neutral position when either or both the phase windings 20 and 21 are deenergized. The local phase winding 20 is continuously energized from the secondary of a local transformer T¹ which receives its energy from the same alternating current source as the local transformer T at the switch TS. The line-phase winding 21 receives its energy 85 over two line wires in accordance with the position of the point detector contacts PD at the track switch TS. The contact 22 of the SS relay operably controls the energization 90 of the indication magnet 15 in conjunction with an energy saving contact 23 which may be actuated to a contacting position by the control of a lever latch 24, also in conjunction with certain contacts governed by the 95 lever L.

100 105 110 115 The switch machine SM is operably controlled by power from a suitable battery BT or any other suitable source of electrical energy. The current, flowing from the positive terminal of this battery BT, passes through the windings of a power lock PL which actuates a locking member 25 to an active position when such current is flowing. The locking member 25 when in an inactive position as shown, allows the lever L to be moved in accordance with the various other locking devices, of which the indication latch mechanism IM is shown. However, when the lever L has been moved to a new governing position causing power current to flow so that the 120 125 130

locking member 25 is in an active position, the lever L may be returned toward its former governing position only so far as to break the circuit for the power applied when in the new governing position. A predetermined time after the power current ceases to flow, the locking member 25 assumes an inactive position so that the control lever L may be returned to its former governing position. Thus, the lever L is prevented from being quickly returned from a new governing position to the former governing position.

It is believed that the usefulness and operation of such a system will be more readily understood by further description being given from the standpoint of operation of the interlocking system taken as a whole.

Operation of the system

With the apparatus and the circuits of the interlocking system in the normal condition as shown, the contact 22 of the SS relay is in a right hand energized position, as the local winding 20 is continuously energized from the secondary of transformer T¹ and the line phase winding 21 is energized over a normal circuit completed with the track switch TS and the switch machine SM in a normal locked condition.

The normal energizing circuit for the line phase winding 21 of the SS relay is traced as follows:—from the right hand terminal of the secondary of transformer T, through wires 30 and 31, contacts 8—32, wires 33, 34 and 35, line phase winding 21 of the SS relay, wires 36 and 37, contacts 9—38, wires 39 and 40, to the left hand terminal of the secondary of transformer T.

Let us assume that the operator desires to reverse the track switch TS, and to do so presses the lever latch 24 preparatory to moving the lever L in a left hand direction. This operation closes an energizing circuit through contact 23 for energizing the indication magnet 15 through a circuit traced as follows:—from the positive terminal of a suitable source of electrical potential indicated as B+, through contact 22 in a right hand position, wire 42, contacts 14—43, wires 44 and 45, windings of indication magnet 15, wire 46, closed contact 23, to the negative terminal of the suitable source indicated as B-.

Assuming the detector track section associated with the track switch TS to be unoccupied, the associated lever lock (not shown) will also be energized at this time, and the lever L may be moved to the new governing position RI. When such movement is made, the circuit for the energization of the indication magnet 15 is opened at the contacts 14—43 as soon as the lever L leaves the position NI. Also, the plunger 16 is caused to assume an active locking position by a projec-

tion 47, so that the lever L can not be moved beyond the position RI.

With the lever L in the reverse indicating position RI, the reverse operating circuit for the switch machine SM is completed by the movable contact 12 so that power operating current flows from the positive terminal of the battery BT through wire 50, the windings 51 of the power lock PL, wire 52, fuse F, wire 53, contacts 12—54, wires 55 and 6, through the operating circuits of the switch machine SM to operate the switch machine motor, through the common wire C to the negative terminal of battery BT. Current flowing in this circuit operates the switch machine SM in the usual well known manner which is more specifically discussed in my above mentioned Patent No. 1,436,903.

This operating current of the switch machine SM operates the locking member 25 of the power lock PL to an active locking position so that should the lever L be quickly returned in a direction towards its former governing position NI, a projection 48 on the lever L would be engaged to prevent movement further than to permit the movable contact 20 to break the power operating circuit just traced. However, after the power current is broken, the locking member 25 slowly releases so that the lever L may be returned to its former governing position NI after a predetermined period of time.

Assuming the lever L to remain in the position RI and the switch machine SM to operate, the contact block 7 is operated to an intermediate position as soon as the track switch TS is unlocked which causes the contact 22 to assume an intermediate position as its energizing circuit is broken at the contacts 8—32 and 9—38. Also, the shunt contacts 10 and 11 assume their biased contacting positions, completing a shunt path from wire 35, through shunt contact 10, wire 49, shunt contact 11, to the wire 36, which path shunts out all foreign currents.

When the switch machine SM has operated the track switch TS to a reverse locked condition, the movable contact block 7 is operated to a reverse extreme position and the shunt contact 11 is actuated to a non-contacting position. Thus, a reverse energizing circuit for the line-phase winding 21 for the SS relay is established through a circuit traced as follows:—from the right hand terminal of the secondary of transformer T, through wire 30, contacts 9—56, wires 57 and 26, winding 21 of the SS relay, wires 35, 34 and 58, contacts 8—59, wire 40, to the left hand terminal of the secondary of transformer T.

With the reverse energizing circuit for the line-phase winding 21 of relay SS completed, the contact 22 is caused to assume a left hand energized position, in which posi-

tion a circuit is completed for energizing the indication magnet 15 of the indication latch mechanism IM, when the lever latch 24 is actuated to close the contact 23. This energizing circuit for releasing the indication latch mechanism IM is traced as follows:— from the positive terminal of a suitable source of electrical potential indicated as B+, through contact 22 in a left hand position, wire 60, contacts 14—61, wires 62 and 45, windings of indication magnet 15, wire 46, closed contact 23, to the negative terminal of the suitable source indicated as B-. The lever L may now be moved to the position R.

The operation of the interlocking system shown as a specific embodiment of the present invention, has been described from the normal condition to the reverse condition, which is considered sufficient to point out the characteristic features of the present invention. The operation of the system from the reverse condition to the normal condition is merely an inverse function of the operation above described.

There is a period of time after power is applied to the switch machine motor during which said switch machine motor operates to unlock the track switch TS. During this preliminary unlocking period of time, the point detector contacts PD remain in a position in correspondence with the track switch TS and its locked condition, thus the contact 22 of the SS relay indicates in the tower that the track switch is in a certain position and locked during the time that the switch machine motor is operating to unlock the track switch.

Without the power lock PL the possibility arises that the control lever L may be moved from the position NI to the position RI and then quickly returned to the position NI before the track switch TS becomes unlocked. With the lever L in the position NI and the contact 22 of the relay SS in a normal position the indication latch mechanism IM may be actuated to a released condition so that the lever L can be returned to its full position N. However, during the time that the control lever L was in the position RI, the switch machine SM may receive sufficient power to give it momentum which will carry it beyond the unlocked condition of the track switch TS, so that should the fuse F blow out when the reversal of current upon the switch machine motor occurs, the switch machine motor would continue to rotate in a direction to unlock the track switch TS although the control lever L would be in the full normal position N. Similar improper or false indication of a constant current or battery type indication system has been described in great detail in my pending application Ser. No. 392,138, filed September 12, 1929, entitled "Interlocking systems" and filed of even date herewith.

A contingency, as above pointed out, is unsafe and fully provided for by the provision of the power lock PL which prevents the quick reversal of the lever L while power current is supplied to the switch machine and during a predetermined time thereafter. The slow releasing period of the lock PL is of such duration of time as to prevent the lever L from being returned to a former position until the switch machine has had time to spend such momentum as it may have gained. In other words, the period of time should be slightly greater than that which is consumed by the switch machine in unlocking the track switch TS.

Such an interlocking system has the advantage that the initiation of the switch machine movement is indicated in the tower, so that the control lever L may be governed in accordance therewith. An additional desirable feature is that the control lever L may be returned to a former full position, at any such time that the SS relay indicates the associated track switch TS to be in a particular extreme position and locked. In other words, should the control lever L be moved to a new governing position and the switch machine SM fail for some reason to operate, then the control lever L could be returned to its former full normal position, allowing the mechanical interlocking between levers to be released in a manner to permit other routes to be set up including the track switch TS in its particular position indicated by the SS relay.

One specific construction of devices and arrangement of circuits has been shown as an embodiment of the interlocking system according to the present invention; however, it is to be understood that the various devices and circuit arrangements selected are to facilitate in the disclosure of the nature of the invention rather than its specific form, and it is to be further understood that various modifications and adaptations may be made without departing from the spirit or scope of the invention as demanded by the following claims.

Having described my invention, I now claim:—

1. In an interlocking system, a track switch controlled by a switch machine, a control lever located in a tower and governing said switch machine, and means preventing quick movement of said control lever to a former governing position during operation of said switch machine.

2. In an interlocking system, a track switch controlled by a switch machine, a control lever located in a tower and governing the movement of said switch machine, and means preventing rapid reversal of said control lever to a former governing position during the unlocking of said track switch by said switch machine.

3. In an interlocking system, a track switch controlled by a switch machine, a control lever located in the tower and governing the movement of said switch machine, locking means preventing certain movements of said control lever by use of the operating current of said switch machine for actuating said locking means. 5
4. In an interlocking system, a track switch controlled by a switch machine, a control lever located in a tower and governing the movement of said switch machine, and means active to prevent said control lever from movement from a new governing 10 position to a former governing position until current for said switch machine has ceased flowing for a predetermined period of time. 15
5. In an interlocking system, a track switch operated by a switch machine, a control lever located in a tower and governing the operation of said switch machine, locking means governing the movement of said control lever, said locking means including, a locking member normally inactive, energizing 20 windings for actuating said locking member to an active position, a locking bar controlled by said control lever and detained from certain movements with said locking member in an active position, and energizing 25 circuits for said energizing windings including the normal and reverse operating circuits of said switch machine. 30
6. In an interlocking system for railroads, a switch machine, a control lever for governing said switch machine, and means governing reversal of said lever only during operation of said switch machine. 35
7. In an interlocking system for railroads, a switch machine, a control lever, operating 40 circuits for said switch machine governed by said control lever, a detent on said lever, a lock plunger for engaging said detent only when actuated, and electro-magnetic means for actuating said lock plunger, said means 45 having windings included in said operating circuits. 50
8. In combination, an operated device, means for operating said device, a control lever governing said operating means, indication means responsive to the condition of said operated device for governing operation of said control lever, and time measuring means retarding operation of said control lever for a predetermined time only 55 when said operating means has been governed thereby providing a time delay to compensate for tardy response of said indication means. 60
9. In combination, one operated device, means for operating said one device, a control lever for governing said operating means, indication means responsive to the condition of said one device, another operated device governed in accordance with said 65 control lever and said indication means, and time measuring means retarding operation 70 of said control lever from a new governing position to a former governing position for providing a time delay to compensate for tardy response of said indication means, whereby said another device cannot be improperly governed. 75
10. In combination, a controlled device, a lever for controlling said device, locking means preventing movement of said lever from a particular intermediate position to a corresponding extreme position except when actuated, indication means capable of actuating said locking means when said lever is in correspondence with said device, and a time delayed lock for restraining movement 80 of said lever, whereby movement of said lever is delayed for a time sufficient to compensate for the tardy response of said indication means to thereby prevent said locking means from being improperly actuated. 85
11. In an interlocking system for railroads, a track switch, a switch machine, a control lever, operating circuits for said switch machine governed by said control lever, an indication latch mechanism preventing movement of said control lever from a particular intermediate position to a corresponding extreme position, indication means capable of actuating said indication latch mechanism to release said control lever when 90 said track switch and said control lever are in correspondence, a detent on said lever, a lock plunger for engaging said detent when actuated, and electro-magnetic means for actuating said lock plunger, said means having windings included in said operating circuits, whereby said indication latch mechanism may not be improperly actuated to release said control lever. 95
12. In an interlocking system for railroads, a track switch, a switch machine for operating said track switch, a control lever having two intermediate positions and two corresponding extreme positions, operating 100 circuits for said switch machine governed by said control lever, an indication latch mechanism preventing movement of said control lever from a particular intermediate position to a corresponding extreme position, indication means capable of actuating said indication latch mechanism to release said control lever when said track switch and said control lever are in correspondence, a power lock for preventing movement of said control lever from one to the other of its said 105 two intermediate positions when actuated, and electro-magnetic means for actuating said power lock, said electro-magnetic means having windings included in said operating circuits of said switch machine. 110
13. In an interlocking system for railroads, a power-operated switch machine having normal and reverse operating circuits, a control lever having normal and reverse extreme positions and normal and reverse indication positions, contacts operated by said 115 120 125 130

control lever, said contacts closing said normal operating circuits when said lever is in corresponding normal extreme and indication positions and closing said reverse operating circuits when said lever is in corresponding reverse extreme and indication positions, a detent on said control lever, a lock plunger for engaging said detent when actuated to thereby prevent movement of said control lever from one to the other of its indication positions but permitting the opening of said operating circuits, and electro-magnetic means for actuating said lock plunger, said electro-magnetic means having 15 windings included in said normal and reverse operating circuits.

14. In an interlocking system for railroads, a power-operated switch machine having normal and reverse operating circuits, 20 a control lever having normal and reverse governing positions, contacts operated by said control lever, said contacts closing said normal operating circuit when said control lever is in a corresponding normal governing 25 position and closing said reverse operating circuit when said control lever is in a corresponding reverse governing position, a detent on said control lever, a lock plunger for engaging said detent when actuated for preventing movement of said control lever from 30 one to the other of said governing positions but permitting the opening of said operating circuits, and electro-magnetic means for actuating said lock plunger, said electro-magnetic means having windings included in said 35 normal and reverse operating circuits.

In testimony whereof I affix my signature.
WINTHROP K. HOWE.
